UNITED STATES PATENT OFFICE.

CHARLES A. SMITH, OF HOPEDALE, MASSACHUSETTS, ASSIGNOR TO DRAPER COMPANY, OF HOPEDALE, MASSACHUSETTS, A CORPORATION OF MAINE.

ROTATABLE SPINDLE AND BOBBIN.

No. 890,881.

Specification of Letters Patent. Patented June 16, 1908.

Application filed August 27, 1907. Serial No. 390,310.

To all whom it may concern:

Be it known that I, CHARLES A. SMITH, a citizen of the United States, and a resident of Hopedale, in the county of Worcester and State of Massachusetts, have invented an Improvement in Rotatable Spindles and Bobbins, of which the following description, in connection with the accompanying drawing, is a specification, like letters on the drawing representing like parts.

This invention relates to rotatable spindles of the type wherein the bobbin is engaged and driven with the spindle by or through the medium of centrifugally-acting clutching means, comprehending members rotated by and with the spindle and loosely connected therewith, to be caused by centrifugal force to firmly engage the bobbin and thereby effect its rotation in unison with the spindle.

In practice there is at times a tendency of the bobbin to swing or move laterally, out of true, particularly at the lower or butt end, notwithstanding the driving engagement of the centrifugally-acting clutching members. Such movement of the bobbin gives rise to undesirable vibrations and tends to improperly affect the operation of the apparatus, and various arrangements have been devised to overcome such objection, with more or less success.

My present invention has for its object the production of simple means whereby the lower end or butt of a bobbin is effectually steadied when placed on a rotatable spindle provided with centrifugally-acting clutching means, the construction and arrangement being such that the butt of the bobbin has no lateral movement relative to the spindle, and hence the objections hereinbefore pointed out are completely overcome.

In accordance with my present invention I provide a steadyng portion for the butt of the bobbin, located below the clutching means and fixed with relation to the spindle, the bobbin being bored to provide a part adjacent its butt to receive the steadyng portion with a snug but non-driving fit, and the bore above such part is of a different diameter, to receive and be engaged by the centrifugally-acting clutching means on the spindle. By such construction the proper action of the clutching means is in no way interfered with nor are the many advantageous

features thereof in the least diminished, while the bobbin at its lower end is steadied and maintained true and concentric to the axis of rotation of the spindle.

The novel features of my invention will be fully described in the subjoined specification and particularly pointed out in the following claims.

Figure 1 is a side elevation of a rotatable spindle of the centrifugally-acting clutch type, with the bobbin thereon in section, illustrating one embodiment of my present invention, the blade of the spindle and the barrel of the bobbin being broken out to save space; Fig. 2 is a detail partly in section and partly in elevation, to show the construction of the parts on the spindle; Fig. 3 is a vertical section of the lower portion of the bobbin, showing the bore thereof having adjacent portions of different diameters; Fig. 4 is a horizontal section on the line 4—4, Fig. 1, looking down upon the clutching means and adjacent parts on the spindle.

The spindle 1, whirl 2 having an upturned sleeve 3 by which it is attached to the spindle, the enlarged circular head 4 at the upper end of the sleeve and forming a vertical rest or support for the bobbin B, and the transversely segmental clutching members 5 loosely surrounding the spindle, may be and are all substantially as in various forms of spindles of the centrifugally-acting type now in use.

As shown herein the clutching members 5 are shaped externally in usual manner and are loose at their upper ends, and herein I have shown their lower ends as entering an annular groove or recess 6 formed in the upper end or top of a cylindrical enlargement 7 extended upward from the bobbin-rest 4.

Retaining pins 8 are passed through holes in the lower ends of the members 5, one for each member, to positively connect them with the spindle to rotate therewith and also to prevent their removal, the pins permitting the requisite radial movement of the upper ends of the clutching members due to centrifugal action when the spindle is rotated, while the outer wall of the recess 6 limits such movement.

The enlargement 7 at the lower ends of the clutching means is fixed with relation to the spindle, as will be manifest, and it serves as a

firm lateral support and steadyng device for the lower end or butt of the bobbin, as will be explained.

Referring to Figs. 1 and 2 it will be seen that the diameter of the part 7 is somewhat greater than the diameter of the bobbin-engaging or clutching surface of the clutch members.

The bobbin B is counterbored at its butt end to present a cylindrical part b at the mouth of the bore, immediately adjacent the butt, and a second cylindrical part b' above the part b but of less diameter, and also of greater length as herein shown, Figs. 1 and 3. The part b' forms an internal chamber to receive the clutching means of the spindle, the clutch members 5 being forced outward by centrifugal action to engage the walls of the chamber b' and by such driving engagement the rotation of the bobbin in unison with the spindle is effected. The part b of the bore of the bobbin is of such diameter that it slips onto the enlargement 7 with a steadyng fit, that is, with no appreciable play but with a smooth and relatively snug fit, but in no sense a driving engagement.

As a result of the above construction the butt of the bobbin has no lateral movement relatively to the spindle and runs perfectly true with relation thereto, while the driving connection between bobbin and spindle is effected by the clutching means, as will be obvious.

When the bobbin is applied to the spindle the expanded upper portions of the clutching members are somewhat compressed or pushed inward as they enter the smaller part or chamber b' of the bore, to insure a firm driving engagement therewith.

By reference to Figs. 1 and 3, it will be seen that the barrel of the bobbin adjacent the butt is of relatively small diameter, such form of bobbin having been devised more particularly for use in so-called "feeler" looms, it being desirable to make of small diameter the part of the barrel on which the yarn is wound with which the feeler cooperates. Such bobbins at best have a thin wall at the junction of the barrel with the butt, and in order to maintain the strength of the bobbin when used with centrifugally-acting clutching means, it is absolutely necessary that such means operate within a chamber or opening of the smallest possible diameter. For that reason the part b' of the bore is made of considerably smaller diameter than the part b, for if the diameter of such part b should be continued up the full length of the bore in the bobbin-butt it would so weaken the bobbin at the junction of the barrel with the butt that a relatively slight blow would break the bobbin. This will be clear from an inspection of either Fig. 1 or Fig. 3 of the drawing. Such a uniformly large bore in the butt has been found in practice impracti-

cable and has been given up for the reasons above set forth. The lower end of the bore as b in the butt must be of larger diameter than the upper part or chamber b' because the part b must receive the steadyng portion or enlargement 7 fixed on the spindle, and the enlargement must be made large enough to loosely surround the lower ends of the clutch members 5. It is of great importance, therefore, that the lower chamber in the bobbin butt, *i. e.*, the one adjacent its outer end, shall be of relatively large diameter and it is of equal importance that the upper chamber be of as small diameter as will receive the clutching means, on account of the necessity to maintain as much material as possible in the bobbin at the junction of the barrel with the butt.

The counterboring of the bobbin to provide the two adjacent portions of different diameters is very easily effected, and the steadyng device on the spindle at the same time affords a convenient means for vertically supporting and laterally confining the lower ends of the clutch members.

Having described my invention, what I claim as new and desire to secure by Letters Patent is:—

1. The combination, with a rotatable spindle provided with centrifugally-acting clutching members to drive the bobbin, a cylindrical enlargement fixedly mounted below said members, and positive connection's between the lower ends of said members and the enlargement, effecting their rotation with the spindle while permitting limited radial movement, of a bobbin having its butt bored to receive said enlargement with a steadyng fit and provided with an internal chamber of less diameter to receive and be engaged by the upper ends of the clutching members to drive the bobbin.

2. The combination, with a rotatable spindle provided with centrifugally - acting, transversely segmental clutching members surrounding the spindle and adapted to internally engage and drive the bobbin, a cylindrical enlargement fixed on the spindle and provided with an annular recess to receive loosely the lower ends of said members and radial pins loosely connecting the lower ends of said members and said enlargement, of a bobbin having its bore at the butt of a diameter to receive said enlargement with a steadyng fit and reduced in diameter above to receive and be engaged by the clutching members when thrown outward by centrifugal action, to drive the bobbin in unison with the spindle.

3. The combination, with a rotatable spindle provided with centrifugally-acting and transversely segmental bobbin clutching members, a cylindrical enlargement fixed on the spindle and having an annular recess to loosely receive the lower ends of said mem-

bers, and connections between the lower ends of said members and the enlargement, of a bobbin counterbored at its butt to present internal cylindrical portions of different 5 diameters, the lower portion of larger diameter receiving the enlargement with a steady-
ing fit and the upper portion, of smaller diameter, receiving and being acted upon by the upper ends of the clutching members to 10 drive the bobbin, the outer wall of the annu-

lar recess acting upon the clutching members to limit outward radial movement thereof when the spindle is running bare.

In testimony whereof, I have signed my name to this specification, in the presence of 15 two subscribing witnesses.

CHARLES A. SMITH.
